(57) **CLAIM**

We claim the ornamental design for a profilometer, as shown and described.

DESCRIPTION

FIG. 1 is a perspective view of a profilometer;

FIG. 2 is a front view thereof;

FIG. 3 is a left-side view thereof;

FIG. 4 is a right-side view thereof;

FIG. 5 is a top plan view thereof;

FIG. 6 is a back view thereof;

FIG. 7 is an enlarged view of portion 7-7 of FIG. 2;

FIG. 8 is an enlarged view of portion 8-8 of FIG. 3;

FIG. 9 is an enlarged view of portion 9-9 of FIG. 4;

FIG. 10 is an enlarged view of portion 10-10 of FIG. 5;

FIG. 11 is an enlarged view of portion 11-11 of FIG. 6;

FIG. 12 is an enlarged view of portion 12-12 of FIG. 1;

FIG. 13 is a perspective view of the profilometer; and,
FIG. 14 is an illustrative view of the profilometer thereof
removed to disclose details not otherwise visible.

The subject article is a profilometer used for measuring a
surface profile (such as the extent of flatness) of a thin disk
object (such as a silicon wafer).

The broken lines in the drawings depict unclaimed environmental
subject matter.
